United States Patent Office

Des. 231,636
Patented May 7, 1974

231,636

MAILBOX

Murray M. Fibus, Youngstown, Ohio, assignor to Steel
City Corporation, Youngstown, Ohio

Filed May 25, 1972, Ser. No. 257,071

Term of patent 14 years

Int. Cl. D31—00

U.S. Cl. D74—9 R

FIG. 1

FIG. 2

FIG. 3

FIG. 4

FIG. 1 is a perspective view of a mailbox showing my new design;

FIG. 2 is a rear perspective view thereof; and

FIG. 3 is a perspective view with the lid of the box partially opened and FIG. 4 is a vertical section on line 4-4 of FIG. 1.

The end not seen is a mirror image of the end illustrated. The bottom is substantially plain.

I claim:

The ornamental design for a mailbox, as shown and described.
